UNITED STATES PATENT OFFICE.

ROBERT L. HORSLEY, OF MEMPHIS, TENNESSEE.

BALE-TIE BUCKLE.

Application filed July 2, 1923. Serial No. 649,041.

To all whom it may concern:

Be it known that I, ROBERT L. HORSLEY, a citizen of the United States, residing at Memphis, in the county of Shelby, State of Tennessee, have invented certain new and useful Improvements in Bale-Tie Buckles, of which the following is a specification, reference being had therein to the accompanying drawings.

10 This invention relates to buckles for securing the ends of bale-ties together, and has for its object the improvement of buckle patented by me May 15th, 1923, Number 1,455,204, and buckles of that general class, 15 by providing efficient and more economical means for attaching buckles to one end of bale-ties before the ties are carried to the press.

In the cotton baling industry there are 20 certain limits to the weight of material that may be used to constitute the buckles. Necessity for economy and established regulations of tare cause this restriction and there is at present no general use of buckles of 25 the type herein described for baling cotton, for the apparent reason that they have not been made efficient without the use of an excess weight of material.

Buckles of this class would be in great 30 favor at the compresses because of the ease and possible speed in their use and my invention makes it possible to produce efficient buckles without any excess in use of material in their manufacture.

35 With these objects in view and other objects that may appear to those skilled in this industry, my invention comprises certain novel combinations, constructions and arrangements of parts as will be described, illustrated in the accompanying drawings, and particularly pointed out in the appended claims.

The word band is used freely to denote bale-tie.

45 In the drawings:

Figure 1 is a front view of my buckle made from steel plate and Figure 2 is the same, showing broken sections, 8, 9, of band applied thereto.

50 Referring to Fig. 1, the buckle comprises band supporting members 1, 1^a and 2, in-

tegral with connecting side bar 3 and separated from each other by a slot 4, forming an opening into the buckle for an entrance of one loop of the band at side of the buckle. 55

The member 1, 1^a is provided with slotted perforation 5, cut parallel to slot 4, the outer end of the two bars formed being left connected by an uncut section 6.

The perforation 5 is made to extend into 60 connecting side 3 far enough beyond and overlapping the open slot 4 to secure the correct width for receiving one end of the band.

Member 2 is preferably provided with re-tentive device described in the aforementioned patent, the said device consisting of an outleaning incline 7, projected upon the inner edge of member near its outer end. A band when applied to this member and 70 strain comes upon it will be wedged between incline 7, and side 3 in a manner to prevent band from shifting or creeping upon the buckle.

Heretofore the perforation 5 has been 75 made to register with the band-seating surface of member 2 and additional width of material had to be provided in order to secure bars 1 and 1^a in combined support, but in the construction described an extra width 80 is obviated without detriment to strength of the buckle.

In using the buckle one end of the bale-band, 8, is threaded through perforation 5 and bent back. To make the tie, the other 85 end, 9, of band is looped and brought into buckle as shown in Fig. 2.

Having described my invention, what I claim is,—

1. A bale-tie buckle comprising band supporting members, side bar connecting said members at one end, a slot, to receive a looped end of the bale band, separating the members and opening out at one side of the buckle, one of said members having a slotted 90 perforation for receiving the other end of the bale band, said perforation overlapping the slot, extending beyond and into connecting bar and removed from open side of buckle, leaving connected bearing between 95 parts of the member. 100

2. A bale-tie buckle comprising band sup-

porting members, side bar connecting said members at one end, a slot to receive a looped end of the bale band between the members, said slot opening out at one side of the buckle, one of said members having a slotted perforation for receiving one end of the bale band and the other member having an out- leaning incline projected upon its inner edge near the outer end in a manner to lead applied loop of band against side bar. In testimony whereof I hereunto affix my signature.

ROBERT L. HORSLEY.
